UNITED STATES PATENT OFFICE.

GEORGE THEODORE SWEETSER, OF NEW YORK, N. Y.

COLLAR.

Application filed April 23, 1926. Serial No. 104,115.

My invention relates to improvements in collars, and more particularly to collars of the soft fold type. Specifically it is my intention to construct a collar of this general type which is provided with means to hold a tie in correct position with respect to the collar, and which means also cooperates with the tie to retain the ends of the collar, when folded down over the neck band, in their folded position so that the same will not curl up or crease, but will present a neat appearance during the entire period of wear.

So that a clear understanding may be had of my invention, reference is made to the accompanying drawings, of which

Fig. 1 is a front view of the two ends of a soft fold collar embodying my invention, with the folds down as ordinarily worn.

Fig. 2 is a front view of a portion of one end of a soft fold collar with the foldable collar portion raised, and

Fig. 3 is an edge view of Fig. 2.

In the drawings A represents a soft fold detachable collar with the usual neck band 25 B and the collar portion C adapted to be folded down over the neck band on the line of juncture D of the band and collar. Adjacent each end of the upper side or outer ply of the band B and to each end of the under 30 side or inner ply of the collar portion C I attach a strip of tape E by stitching the same at the ends thereof to the band and collar part respectively. This tape E is so positioned that the outer edge portion thereof 35 lies in a plane approximately parallel with the outer edge of the collar portion C. As shown by the drawings, the tape E is preferably tapered downwardly throughout its length from that end thereof which is attached to the collar part C.

Approximately at a point where the tape overlies the lining of juncture of the collar part and the band, I bridge or cross the same with a relatively short, narrow strip of tape 45 or cloth F which is secured by stitching to the collar part on each side of the large tape E. The distance from the small tape F to the line of attachment of the large tape E to the collar part A is preferably greater than the 50 distance from the tape F to the line of attachment of the larger tape to the band B.

By the above construction, it will be noted that the tape E is relatively loose between its ends which are attached to the collar part and the band part respectively, but is held down by the small cross tape F. This construc-

tion provides a decided improvement in this particular art, as it will be readily appreciated that after the tie is threaded through the upper loop of the tape i. e. that part lying 60 between the small tape F and the line of attachment to the collar part A, thus can be had an adjustment of the tape E or a lengthening of the loop portion thereof which embraces the tie, and when the collar part is 65 folded over the band portion and assumes the position used in wearing, the cross tape F will prevent the tie from slipping down out of place. Also the tie being threaded through the loop part of the tape carried by the collar 70 portion C will hold the end of the collar part smoothly in place and prevent the same from curling up or wrinkling, and thus presenting an unsightly appearance during wear.

One great advantage in providing the adjustment of the tape or the adjustable loop in the tape is that any width of tie can be passed therethrough, whereas if the same were not adjustable only the comparatively small or narrow portion of the tie band could pass through the loop. In other words, the loop would be limited as to length if not adjustable, and thereby would limit the amount of the adjustment of the tie band around the collar and also limit the length of tie that 85 could be exposed by the wearer. Also the loop of the tape embracing the tie will slide through the cross tape F whenever any pressure or pull is exerted upon the end of the tape.

By the above described construction, it will be appreciated that I have provided a comparatively simple means to hold the tie in place on the collar and one which holds the collar naturally in place without wrinkling 90 or curling up, and also one that is hidden from all view and will assure the correct position of the tie with respect to the collar, and further will allow for any "give" of the collar band or tie while being used.

Having thus described my invention, what I claim is:

1. A soft fold collar comprising a band part and a collar part, a tape positioned near the ends of the collar and band parts, the ends of the tape being secured to the under side of the collar and outer sides of the band parts respectively with the intermediate portion of the tape being relatively loose with respect to the collar and band parts and a bridging piece supporting the tape intermediate the ends thereof, which bridging piece per-

mits movement of the tape in the direction of its length relative to the collar.

2. A soft fold collar comprising a band part and a collar part, a tape positioned near the ends of the collar and band parts, the ends of the tape being secured to the under side of the collar and outer sides of the band parts respectively with the intermediate portion of the tape being relatively loose with respect to the collar and band parts, and a cross strip of fabric bridging the tape intermediate the ends thereof.

3. A soft fold collar comprising a band part and a collar part, a tapered strip of tape positioned near the ends of the collar and

band parts with the outer edge portion thereof lying approximately parallel with the outer edge of the collar part, the ends of the tape being secured to the under side of the collar part and outer side of the band part 20 respectively with the intermediate portion of the tape being relatively loose with respect to the collar and band parts, and a relatively small cross strip of fabric bridging the tape at a point adjacent the line of junction of the band and collar parts, the cross strip being attached at each of its ends only to the under face of the collar part. 25

In testimony whereof I affix my signature.
GEORGE THEODORE SWEETSER.
